UNITED STATES PATENT OFFICE.

ALVIN DONALDSON WICK, OF TOPEKA, KANSAS, ASSIGNOR OF ONE-THIRD TO WILLIAM W. WICK, JR., OF PORTLAND, OREGON:

CRUTCH.

No. 870,400.

Specification of Letters Patent.

Patented Nov. 5, 1907.

Application filed March 19, 1907. Serial No. 363,256.

To all whom it may concern:

Be it known that I, ALVIN DONALDSON WICK, a citizen of the United States, and a resident of Topeka, in the county of Shawnee and State of Kansas, have invented a new and Improved Crutch, of which the following is a full, clear, and exact description.

This invention relates to crutches, and the object of the invention is to produce a crutch the length of which can be adjusted to suit persons of different height.

A special object of the invention has been to provide a construction which will accomplish this object without the use of springs or similar contrivances likely to get out of order.

15 The invention consists in the construction and combination of parts to be more fully described hereinafter and particularly set forth in the claims.

Reference is to be had to the accompanying drawings forming a part of this specification, in which similar characters of reference indicate corresponding parts in all the figures.

20 Figure 1 is a side elevation of a crutch constructed according to my invention; Fig. 2 is a longitudinal vertical section through the lower portion of the crutch; and Fig. 3 is a cross section on the line 3—3 of Fig. 2.

Referring more particularly to the parts, 1 represents the body of the crutch, which is formed into forks 2 that extend up integrally from a crotch 3. In the crotch 3 there is provided a stem or spindle 4 which 25 extends downwardly within the leg of the crutch, as shown in Fig. 2. This leg includes a main leg section 8 and removable blocks, as will appear presently. This stem is threaded throughout its length as indicated, so as to receive a nut 6, said nut being received 30 in a recess 7 formed in the side of the main section 8 of the leg. The stem 4 is disposed centrally in this main section 8, and the section is of round form as indicated. Between the upper end of the main leg section 8 and the crotch 3, I provide a plurality of removable blocks 9 which have centrally disposed openings 35 through them to receive the stem 4, as will be readily understood. Upon the lower end of the leg section 8 I provide a tip 10 of suitable form. As indicated in

Fig. 3, the recess 7 opens upon the side face of the main section 8 and extends inwardly so that the nut 6 may 45 be slid into the recess when the parts are being assembled. The blocks 9 may be of different widths or thicknesses, as shown. If the person using the crutch is unusually tall, the number of blocks used may be increased, and if the person is unusually short, some of 50 the blocks may be removed. In this way the length of the crutch may be accurately adapted to the height of the person using it.

It should be understood that the nut 6 is permanently set in the recess, and a plug 6^a is placed in the 55 recess behind the nut; the outer face of the plug is flush with the side of the crutch so that the appearance of the crutch is not detracted from in any way.

Special attention is called to the fact that the crutch always presents a rigid structure at the leg, without 60 employing springs or other parts which can get out of order. The invention is particularly useful in hospitals and similar institutions, as it obviates the necessity for providing crutches for patients of different heights. A small number of crutches can be kept on 65 hand and readily adjusted to the proper length.

Having thus described my invention, I claim as new and desire to secure by Letters Patent:

1. A crutch having a body and a main leg section removably attached thereto, and removable blocks between 70 said main leg section and said body and adapted to be removed or replaced to change the length of the crutch.

2. A crutch having a body with a stem extending downwardly from the lower end thereof, and a leg attached to 75 said stem and having a plurality of removable blocks adapted to change the length of the crutch.

3. A crutch having a body with a threaded stem extending downwardly from the lower end thereof, a plurality of blocks received over said stem, a main leg section below said blocks and having a recess in the side thereof, 80 and a nut mounted in said recess and received on said stem.

In testimony whereof I have signed my name to this specification in the presence of two subscribing witnesses.

ALVIN DONALDSON WICK.
